UNITED STATES PATENT OFFICE.

BENJAMIN R. DETWILER AND HENRY L. RAAB, OF WASHINGTON, DISTRICT OF COLUMBIA.

DESIGN FOR A MILK BOTTLE.

Application filed August 28, 1926. Serial No. 18,896. Term of patent 14 years.

To all whom it may concern:

Be it known that BENJAMIN R. DETWILER and HENRY L. RAAB, citizens of the United States of America, residing at Washington city, District of Columbia, have invented a new, original, and ornamental Design for Milk Bottles, of which the following is a specification, reference being had to the accompanying drawing, forming a part thereof, and wherein—

Figure 1 is a view in perspective of a milk

bottle, showing the new design as applied.

Figure 2 is a bottom plan view of the milk bottle with the new design shown applied.

What is claimed is:

The ornamental design for a milk bottle as shown.

In witness whereof the inventors' signatures are hereunto affixed.

BENJAMIN R. DETWILER.
HENRY L. RAAB.
